UNITED STATES PATENT OFFICE.

WILLIAM T. McNINCH, OF CHICAGO HEIGHTS, ILLINOIS, ASSIGNEE TO AMERICAN MANGANESE STEEL COMPANY, OF CHICAGO, ILLINOIS, A CORPORATION OF MAINE.

RAILWAY CROSSING.

Application filed August 30, 1924. Serial No. 735,156.

This invention relates to railway crossings in which intersecting treads, guards, and flangeways are formed in a single casting. In crossings of this kind it is found that cracks are liable to develop in the bottoms of the flangeways at and adjacent to the point of intersection, and to grow under continued stresses incident to use until the casting is endangered; such cracks being probably due to the concussion of the wheel against the far side of the flangeway which it is crossing, while the wheel still bears against the edge of the near side.

The object of the present invention is to so design a crossing of the kind described, that it will offer greater resistance to the tendency to crack under the stresses incident to use, and the invention proceeds upon the principle of developing such vertical dimension in the side walls of the flangeways as will insure substantial resiliency in said walls and adapt them to absorb a sufficient portion of the wheel shock, which would otherwise be imparted to the web which constitutes the flangeway bottom, to thereby save the latter from destructive strains.

In the preferred embodiment of the invention which is selected for purposes of illustration, the abnormal depth of the flangeways exists not only at their intersection, but continues in each flangeway, in opposite directions from the point of intersection a distance proportional to the range of influence of wheel shock to be guarded against, and then gradually decreases until it merges with the normal depth of the flangeway at points where wheel shock becomes substantially dissipated.

In the accompanying drawing—

Figure 1 is a plan view, and Figure 2 a section on the line 2^x—2^x of Figure 1, of a railway crossing designed in accordance with the distinguishing principle of the present invention.

1 represents the treads, 2 the guards, and 3 the flangeways of a crossing. While the flangeways 3 are ordinarily formed at a depth which is merely sufficient to afford ample clearance for the flanges of the wheels, for instance, a depth about equal to the width of the flangeway, the present invention develops these flangeways with their bottoms 3^a at such a low level at and

adjacent to the point of intersection 4 of the crossing as to give a depth of flangeway at such point which is much greater than (for instance, about twice) the width thereof, or of the web or bottom of the flangeway which it is to protect, so that the vertical walls of these flangeways at and adjacent to the intersection will have a dimension such as indicated at X in Figure 2, instead of the normal dimension such as indicated at Y in said figure, with the result that resiliency will be developed in these side walls of an order that is sufficient to largely absorb the shock transmitted by the wheel as it crosses the intersecting flangeway, instead of imparting said shock to the bottom of the flangeway, and with avoidance of, or such substantial reduction in the flexure of the web at the point 4 as will prevent overreaching the elastic limit or development of crystallization of the metal, or other adverse influences, which, with flangeways of normal depth, have been found to produce cracks and impair the lasting quality of the crossing.

While the lower level of flangeway web 3^a is shown extending in a horizontal line an appreciable distance on either side of the intersection 4, and thereafter merging through inclines 3^b with the normal depth of the flangeway 3, it is obvious that the angle of inclination might be changed, or the substantially straight portion of the lower level web might be increased, without departing from the spirit of the invention.

I claim:

1. A railway crossing having intersecting flangeways, a flangeway at the point of intersection having a depth substantially greater than its width, and the side walls which define said flangeway having inherent resiliency sufficient to absorb a substantial portion of shock incident to a car wheel crossing the flangeway.

2. A railway crossing having a tread portion interrupted by an intersecting flangeway, and having said flangeway at a greater depth immediately adjacent the point of intersection than at points remote therefrom.

3. A railway crossing having a tread portion interrupted by an intersecting flangeway, and having said flangeway at a greater depth immediately adjacent the point of in-

tersection than at points remote therefrom, and having such depth gradually merge from the greater into the lesser dimension.

4. A railway crossing, comprising members forming an interrupted tread portion and constituting side walls of a flangeway intersecting said tread portion, said side walls being united by an integral web forming the bottom of the flangeway, said web being located in a plane sufficiently below the upper surfaces of said tread members to make the height of said walls materially greater than the distance between the walls, and to develop in said walls resiliency sufficient to absorb a substantial portion of shock incident to a car wheel striking the far wall in crossing the flangeway.

5. A railway crossing, comprising intersecting tread portions, and intersecting flangeways each subdividing the tread portion into two members which constitute side

walls of such flangeway, each flangeway including a web portion integrally uniting said side walls; the web portions at and adjacent to the intersection of the flangeways 25 being located at a level substantially lower than the normal depth of flangeway and developing in the side walls vertical dimensions sufficient to reduce bending strains in the bottom forming webs.

6. A railway crossing having intersecting flangeways in which a flangeway at and adjacent to the point of intersection of the flangeways has a depth approximately twice its width, and the side walls of said flangeways having substantial resiliency in the direction of shock imposed by a wheel crossing the flangeway.

Signed at Chicago Heights, Illinois, this 19th day of August, 1924.
